(57) **CLAIM**

The ornamental design for generator housing, as shown and described.

DESCRIPTION

FIG. 1 is a top perspective view of generator housing illustrating a first embodiment of our new design;

FIG. 2 is a bottom perspective view thereof;

FIG. 3 is a top plan view thereof;

FIG. 4 is a bottom plan view thereof;

FIG. 5 is a side view thereof, the opposite side view being a mirror image;

FIG. 6 is another side view thereof;

FIG. 7 is another side view thereof;

FIG. 8 is a cross section view thereof taken along the broken line 8-8 in FIG. 3;

FIG. 9 is a top perspective view of generator housing illustrating a second embodiment of our new design;

FIG. 10 is a bottom perspective view thereof;

FIG. 11 is a top plan view thereof;

FIG. 12 is a bottom plan view thereof;

FIG. 13 is a side view thereof, the opposite side view being a mirror image;

FIG. 14 is another side view thereof;

FIG. 15 is another side view thereof; and,

FIG. 16 is a cross section view thereof taken along the broken line 16-16 in FIG. 11.

The dashed broken lines in the drawings illustrate portions of the generator housing that form no part of the claimed design.

For clarity of illustration, the cross section views in FIGS. 8 and 16 show only the material at the plane of the cross section and not material beyond the plane of the cross section.
